DESIGN FOR A TAXICAB CRUISING LIGHT

Charles D. Nelson, Jr., Arlington, Va.

Application October 30, 1947, Serial No. 142,205

Term of patent 14 years

(Cl. D48—32)

To all whom it may concern:

Be it known that I, Charles D. Nelson, Jr., a citizen of the United States, residing at 4828 Lee Boulevard, in the city of Arlington, county of Arlington, and State of Virginia, have invented a new, original, and ornamental Design for a Taxicab Cruising Light, of which the following is a specification, reference being had to the accompanying drawing, forming part thereof.

Fig. 1 is a top plan view of a taxicab cruising light showing my new design;

Fig. 2 is a side view thereof; and

Fig. 3 is a perspective view thereof.

I claim:

The ornamental design for a taxicab cruising light, as shown.

CHARLES D. NELSON, JR.
